Primary Examiner—Jeffrey Asch

(57) **CLAIM**

I claim the ornamental design for a turtle-shaped combined bottle opener and beer separator, as shown and described.

DESCRIPTION

FIG. 1 is a perspective view of a turtle-shaped combined bottle opener and beer separator showing my new design. FIG. 2 is a left side elevation view thereof, the right side elevation being a mirror image thereof;

FIG. 3 is a top elevation view thereof;

FIG. 4 is a bottom elevation view thereof;

FIG. 5 is a rear elevation view thereof; and,

FIG. 6 is a front elevation view thereof.
